[57] CLAIM

I claim the ornamental design for a modular hunting backpack and vest, as shown and described.

DESCRIPTION

FIG. 1 is a perspective view of a modular hunting backpack and vest showing my new design, a more accurate indication of the rear surface of the article being shown in FIG. 3; FIG. 2 is a front elevation view thereof; FIG. 3 is a back elevation view thereof; FIG. 4 is a left side elevational view thereof; FIG. 5 is a right side elevational view thereof; FIG. 6 is top view thereof; and, FIG. 7 is a bottom view thereof.

The broken lines showing a human torso in FIG. 1 are for illustrative purposes to show how the article is used, said lines forming no part of the claimed design; and the broken lines shown on the surface of the claimed article throughout the views are understood to represent stitching.
